Attest:

UNITED STATES PATENT OFFICE.

CHARLES E. SARGENT, OF INDIANAPOLIS, INDIANA.

INTERNAL-COMBUSTION ENGINE.

Application filed June 27, 1919. Serial No. 307,160.

To all whom it may concern:

Be it known that I, CHARLES E. SARGENT, a citizen of the United States, residing at Indianapolis, in the county of Marion and

6 State of Indiana, have invented a new and useful Improvement in Internal-Combustion Engines, of which the following is a specification.

10 My invention relates to certain new and useful improvements in internal combustion engines of the Diesel type.

An object of this invention is to provide an improved means for injecting the fuel oil into the cylinder so as to get a more intimate 15 mixture of fuel and air whereby the resulting charge will burn more completely and evenly, thereby increasing the efficiency of the engine and decreasing the tendency of carbon to deposit on the walls of the combustion chamber, valves, etc.

This and other objects as will appear in the following specification are accomplished by my invention which is herein described and covered by the appended claims.

25 Referring now to the drawings,

Figure 1 is a longitudinal section through one of the cylinders of an engine embodying my invention; Fig. 2 is a longitudinal section through the fuel pump; Fig. 3 is a section on the line 3 of Fig. 2; Fig. 4 is a longitudinal section on the line 4 of Fig. 1 at right angles to that shown in Fig. 1; Fig. 5 is a radial section on the line 5 of Fig. 4; Fig. 6 is an enlarged section of the top of 30 the cylinder showing the pressure piston approaching the end of its downward movement; Fig. 7 is a similar section with the pressure piston up; Fig. 8 is a horizontal section on the line 8 of Fig. 7, and Fig. 9 is 35 a diagram showing the positions in which the various movements of a cycle occur.

The engine herein illustrated is of the liquid fuel type. Its novelty lies primarily in the means for introducing the liquid fuel, and this device can be applied, if desired, either to two or four cycle engines. The engine here shown is a four-cylinder two-cycle engine, one cylinder only being illustrated, since that clearly shows the principles of my 45 invention, but the fuel-pump will be seen to have connections for feeding fuel to four cylinders.

50 Referring to the drawings, 10 is the cylinder and 11 the crank-case in which is journaled the crank-shaft 12 having disks 13 forming a fly-wheel and connected by a crank-

pin 14 on which is pivoted a pitman 15 connected to the piston 16 through the medium of the usual wrist-pin 17. The fly-wheel disks 13 are provided with openings 18 (Fig. 60 4) which, as the fly-wheel rotates, come into registration with hollow thimbles 19 (Fig. 5) extending through the crank-case wall and pressed inwards against the fly-wheel disks by springs 20. As is shown by dotted lines in Fig. 4, there are two of these thimbles 19 so that the crank-case is connected through one or the other with the atmosphere during the entire rise of the piston. Air thus flows into the crank case from the 70 atmosphere during the entire rise of the piston as is common in two-cycle engines.

21 (dotted lines Fig. 4) is the exhaust and 22 the intake port. These ports are uncovered by the piston in its descent in the usual way, their timing being shown on Fig. 9. The exhaust opens at the end of 121° of downward movement of the crank, that is 59° from the bottom of the piston-stroke while the intake opens 45° from the bottom 80 of the stroke. Thus, as the piston descends, the exhaust first opens, permitting the cylinder pressure to fall approximately to atmospheric, and later the intake opens permitting the air compressed in the crank case to flow 85 in and scavenge the cylinder.

23 is a fuel-pump shaft, which is driven by a worm gear on the main shaft, and in a two-cycle engine at the same speed. The shaft has a flat place 24 which operates as a 90 cam to reciprocate the pump-pistons 25, each of which is inwardly pressed by a spring 26. The fuel comes into a reservoir 27 at the back of the pump, thence through a pump-intake valve 28 into the space above 95 the pump piston. As the piston reciprocates the fuel is forced out through a pump-exhaust 29 into a fuel pipe 29a. The timing of the pump cam is that illustrated on the Figure 9; that is, the pump-piston moves 100 in for the first 45° of the second quadrant of the descent of the main piston and moves out to deliver fuel-oil during the second 45° of this quadrant. For the other three quadrants of the movement of the crank the 105 pump-piston is stationary. Thus the fuel delivery occurs when the intake and exhaust valves are both open and there is therefore no necessity for delivering it against high pressure.

110 For the purpose of delivering the fuel to the engine cylinder at the time when there

is sufficient air-pressure therein to ignite the fuel spontaneously, as in the Diesel type of engine, I provide a pressure piston 30 in the cylinder-head. This piston has a downwardly projecting hollow stem or nozzle 31 reciprocating in a corresponding opening in the cylinder-head. The pressure piston is reciprocated by a rocker-arm 32 driven by a push-rod 33 the end of which bears on a cam 34 on the main shaft. The timing of the pressure piston is shown in Figure 9. The pressure piston starts up $26\frac{1}{2}^{\circ}$ from the beginning of the second quadrant of the crank circle and reaches the top of its movement when the crank is at the bottom of its stroke. Thus it is moving up at the time when the fuel is being delivered and so opposes no resistance to its entrance. The stem of the pressure piston, as has been heretofore stated, is hollow, and is provided with perforations 35 entering its central hollow tangentially, as shown in Figure 8. The position of these perforations 35 is such that when the piston is up they are uncovered, as shown in Figure 7, so that the space under the pressure piston is filled with gas passing up through the stem 31 and out through these perforations. The fuel thus enters an annular space 36 beneath the pressure piston and at a height to register with the perforations 35 when the pressure piston is at its lowest point of movement. The annular space has communication through an opening 37 with the space under the pressure piston. Backward movement of the fuel is prevented by a valve 38. The operation of the fuel-injection will now be readily apparent. As the main piston moves up, compressing the air in the cylinder to the high point desired in engines of this character, that is, approximately 500 pounds to the square inch, the space beneath the pressure piston which is filled with burnt gas fills up further with gas and air at considerable pressure 41° before the piston reaches the upper end of its movement, the pressure piston starts down trapping the gas and air beneath it. When the main piston reaches the top of its stroke and is just ready to receive the force of combustion upon it the pressure piston is nearly at the bottom of its stroke, as shown in Figure 6, when the gas and air beneath the piston is compressed to a very high degree above the oil in the annular space. This pressure approximates 1000 pounds to the square inch, and is thus ample to force the fuel into the cylinder against the compression therein. Just as the crank passes the top of its stroke the pressure piston moves down far enough to throw the perforations 35 in its hollow stem or nozzle into registration with the annular space 36, in which is the oil. The high pressure above the oil instantly forces it out through the nozzle 31 into the com-

bustion chamber where it ignites spontaneously. Premature combustion of the fuel in the annular space is prevented by several factors; 1st, the gas above it is largely burned gas for the pressure piston starts to move up before the exhaust opens and is well under way before the intake opens; and, 2nd, the volume of air contained in the space is not sufficient for any very great amount of combustion as only the oxygen on top of the oil in the annular space could ignite in any event. The tangential arrangement of the perforations 35 causes the oil to enter the nozzle in a whirling form so as to enter the cylinder in a condition to mix as rapidly as possible with the air therein.

The arrangement above described thus produces an engine of the Diesel type which can be made in very small sizes and which possesses the high efficiency of the Diesel engines without the attendant disadvantages of a separate high pressure pump. The fuel pump operates at low pressure, driving the oil into an auxiliary chamber which receives gas from the cylinder within when the pressure is raised to an extent sufficient that when the communication with the cylinder is again open the oil will enter with the requisite force.

Since the novelty of the present invention inheres in the fuel-feeding means I have not considered it necessary to show parts of my engine which are totally disconnected therewith, as, for instance, starting means, lubricating means, and the like, nor have I illustrated any means for varying the timing of the fuel injection, since these features are known in the art and can be supplied by a mechanic in the forms which seem to him best to conform to engineering requisites. It will be evident too that if desired the present arrangement can readily be applied to four-cycle engines, the only change necessary being to drive the pressure piston cam and fuel-pump at half the speed of the main shaft, and to supply the valves usually employed in four-cycle engines. These modifications being obvious and within the range of skill of a mechanic but, because of the possibility of making such modifications, I do not intend to limit myself to the specific form herein shown, except as pointed out in the claims, in which it is my intention to claim all the novelty inherent in my structure as broadly as is permitted by the state of the art.

What I claim as new and desire to secure by Letters Patent is:

1. In a Diesel-type engine, a cylinder, a piston therein, a chamber adjacent the cylinder and communicating therewith, means for supplying a measured charge of fuel to said chamber, an auxiliary cylinder, a pressure piston therein, a passage connecting said cylinders, a hollow tube slidable in said passageway, means for moving said tube to

- close communication between said cylinders near the end of the compression stroke of the main piston, means for forcing down the pressure piston for compressing the charge 5 of gas in the pressure cylinder, said tube upon a further movement opening communication between the pressure cylinder and main cylinder through said chamber.
2. In a Diesel-type engine, a cylinder, a 10 piston therein, a chamber adjacent the cylinder and communicating therewith, means for supplying a measure charge of fuel to said chamber, an auxiliary cylinder, a pressure piston therein, a passage connecting said 15 cylinders, a hollow tube slideable in said passageway, and connected to said pressure piston for closing communication between said cylinders near the end of the compression stroke of the main piston, means for 20 forcing down the pressure piston for compressing the charge of gas in the pressure cylinder, said tube upon a further movement opening communication between the pressure cylinder and main cylinder through 25 said chamber.
3. In a Diesel-type engine, a cylinder, a piston therein, a chamber adjacent the cylinder and communicating therewith, means for supplying a measured charge of fuel to 30 said chamber, an auxiliary cylinder, a pres-
- sure piston therein, a passage connecting said cylinders and chamber, an opening connecting the auxiliary cylinder and chamber, a hollow tube connected to said pressure piston and slideable in said passage and normally closing communication between said chamber and cylinder, openings leading into said hollow tube, and means for moving said pressure piston to close said last named openings and to compress the gas in said auxiliary cylinder, said last named openings registering with the chamber as the pressure piston nears the end of its stroke, whereby the charge of fuel is forced through said hollow tube into the cylinder. 35
4. In an internal combustion engine, a cylinder, a piston therein, a chamber adjacent said cylinder, means for supplying a measured charge of fuel to said chamber, means for putting said charge under pressure, a passageway between the chamber and cylinder and a sliding valve in said passageway, said valve having a longitudinal passage opening into said cylinder and openings leading tangentially into said longitudinal passage whereby the charge is introduced into the cylinder in the form of a whirling spray. 40 45 50 55
